UNITED STATES PATENT OFFICE.

CHESTER T. BLISS, OF MELROSE HIGHLANDS, MASSACHUSETTS, ASSIGNOR TO CHETLEW MANUFACTURING COMPANY, A COPARTNERSHIP COMPRISING LEWIS J. SAGE AND HIMSELF, OF MALDEN, MASSACHUSETTS.

ELECTRICAL CHRISTMAS CANDLES.

Application filed October 9, 1925. Serial No. 61,520.

This invention relates to an electric illuminating device, and particularly to a device adapted for use as a window display imparting the effect of a row of lighted candles.

5 The object of the invention is to provide a novel and highly attractive electric illuminating device of the character specified, which is particularly adapted to be used as a window display during the Christmas 10 season to impart the effect of a row of lighted candles without the usual fire hazard attending the use of ordinary candles when used for this purpose.

To this end the invention consists in the 15 device hereinafter described and particularly defined in the claim at the end of this specification.

In the drawing illustrating the preferred embodiment of the invention, Figure 1 is a 20 side elevation of the illuminating device; Fig. 2 is a vertical sectional detail through the base portion of the device; Fig. 3 is a bottom plan with the insulating channel cover removed; Fig. 4 is a sectional detail 25 on line 4-4 of Fig. 3; and Fig. 5 is an enlarged sectional detail through the upper portion of one of the socket supporting members.

Referring to the drawing, the illuminating 30 device illustrated therein is adapted to be used as a window display to impart the effect of a row of lighted candles, and comprises a base portion 10 preferably of wood and of a size adapted to permit the device to 35 be placed upon the ordinary window sill. The base portion 10 is provided with a plurality of socket supporting members 12 mounted thereon and upstanding therefrom. As herein shown, the socket supporting 40 members 12 comprise hollow tubes driven into preformed holes in the upper surface of the base 10 to be secured in fixed relation thereto. The socket supporting members 12 are preferably arranged in alignment and 45 the heights of the different members 12 are preferably arranged to provide a symmetrical appearance having the effect of a series of candles of heights gradually diminishing from the central ones to the end ones in the 50 manner illustrated in Fig. 1. The upper end of each socket supporting member 12 is provided with a socket 14 adapted to receive an electric lamp 15. The sockets 14 are preferably of a size such as to permit

small tapering lamps to be used, which when 55 lighted impart the appearance of a lighted candle to the several socket supporting members 12. Referring to Fig. 5 the socket 14 is illustrated as secured in a plug 16 driven into the upper end of the socket supporting 60 member or tube 12.

The wiring for the several lamp sockets 14 preferably includes a plug 18 of standard 65 construction and wiring 20 extended through a hole in one end of the base portion 10 and through a channel 22 in the bottom of the base 10. The wiring 20 is arranged to extend upwardly through each of the hollow tubes 12 and preferably to connect the several lamp sockets 14 in series. The channel 70 22 is preferably closed by an insulating cover 24 which may be conveniently tacked to the bottom of the base 10.

From the description thus far, it will be 75 observed that in accordance with the present invention an illuminating device is provided which may be placed upon the ordinary window sill so that the several lamps 15 and socket supporting members 12 will be visible from the exterior of the house through 80 the window, and will impart the appearance of a series or row of lighted candles. The present device while serving all of the purposes for which the ordinary tallow candles 85 have heretofore been used, at the same time avoids the fire risk incident to the open candle flame. It is a fact that at Christmas time many fires have resulted from the use 90 of candles displayed in windows because of the liability of curtains and overhangings 95 being blown into the flame. It has been found that by using lamps 15 of relatively small voltage, such for example as fifteen volts, eight of the lamps 15 can be used in series in the ordinary house-lighting circuit carrying a current of approximately 110 100 volts, and this small voltage for each lamp 15 enables it to be made sufficiently small to have the shape and height of the flame of a candle and also enables the supporting members 12 to be made of a diameter of the body portion of the ordinary candle, with the result that the combined effect of the supporting member 12 and the small tapering lamp 15 is that of the ordinary tallow 105 candle.

While in its preferred form the invention contemplates an illuminating device partic-

ularly adapted for use as a window display, it is not desired to limit the invention thereto.

Having thus described the invention, what is claimed is:—

An illuminating device of the character described, comprising an elongated substantially flat portable base capable of being set upon and supported by the sill of a window and provided with a wire-receiving chamber and having in its upper surface a plurality of openings spaced apart and communicating with said wire-receiving chamber, a plurality of tubular members of different

lengths inserted into the openings in said hollow base and projected upwardly from the latter, socket-supporting members inserted into said hollow tubular members and connected with the wires in the chamber in said base, and relatively small tapering lamps of low voltage in said sockets, said tubular members being arranged to decrease in length in opposite directions from the center of the base toward the ends thereof.

In testimony whereof, I have signed my name to this specification.

CHESTER T. BLISS.
